2 Sheets-Sheet 2

UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed August 21, 1923. Serial No. 658,502.

This invention relates to manifolding typewriting machines of the continuous billing type, in which a continuous composite web is fed around a cylindrical platen, the composite web comprising several plies of work-sheets having successive corresponding forms printed thereon, said plies being sometimes separated from each other, and sometimes joined at their side edges to form a fan-folded web, the various plies having carbon-sheets interleaved therebetween. The invention relates more particularly to means to facilitate a relative displacing or shifting between the carbon-sheets and the work-sheets, or, in other words, a shifting of the carbon-sheets from the typed set of forms to a fresh set or untyped set of forms.

In the Underwood continuous billing typewriting machine shown in the patent to Wernery & Smith, No. 1,132,055, dated March 16, 1915, a cylindrical platen is employed, and said platen is displaceable upwardly by means of a swing-frame to permit the composite web to be straightened out preparatory to displacing or shifting the carbon-sheets along the work-sheets to a fresh set of forms. There is also employed, in said machine, a table extending rearwardly from the platen, over which the work-web is conducted from the rear of the machine to the platen, and upon which a carbon-carrier is mounted to travel back and forth, towards and away from the platen, said carbon-carrier having the ends of the interleaved carbon-sheets connected thereto, and being movable rearwardly by a handle while the work-sheets are drawn forwardly to a suitable gage; after which the platen is lowered to its normal printing condition, and the typed set of forms severed.

In my co-pending application Serial No. 645,995, filed June 18, 1923, provision is made to so condition the work-web that there may be a relative shifting between the carbon-sheets and the work-sheets without lifting the platen, the platen remaining always in its usual typing position. For this purpose, there is provided a table having a curvature of comparatively large radius. A rearward extension of said table supports a

carbon-carrier to which the ends of the carbon-sheets are attached, and which may be operated by a handle to push it rearwardly to withdraw the composite web around the platen to free the carbon-sheets from the platen, after which the work-sheets may be fed forwardly around the platen to a suitable gage while the carbon-sheets are held. The carbon-sheets may then be fed with the work-sheets until the leading edges of the work-sheets come to a second gage when the typed set of forms may be severed, the carbon-sheets having reached the printing point.

An object of the present invention is the provision of means to so condition the web that there may be effected a relative shifting between the carbon-sheets and the work-sheets without conditioning the web to form a curvature of large radius from the platen and without straightening out that portion of the web including the carbon-sheets, thus enabling the dimensions of the machine to be kept down to a minimum and producing a simple device which may readily be applied to any standard typewriting machine.

To this end, the invention comprises a rearwardly-extending table over which the work-web is conducted to the platen, said table being connected to suitable brackets on the typewriter-carriage to travel therewith, and disposed with its forward end near the upper edge of the usual rear paper-shelf. A carbon-carrier is mounted to travel back and forth on said table, towards and away from the platen. The various plies of the web pass through the carbon-carrier, where the carbon-sheets become interleaved between the plies, whence the web extends forwardly over the rearwardly-extending table, and bends downwardly at the forward end of said table towards the platen. Suitable bars or separators are provided in the bend of the web at the forward end of said table, said bars being so arranged as to hold the plies of the web separated from each other so as to avoid touching and consequent binding of the plies against the carbon-sheets, thus affording freedom of the carbon-sheets and permitting

- the work-sheets to be shifted relatively thereto around said bend without smudging. Each bar is effective to guide one of the plies and its superposed carbon-sheet.
- 5 The bars are detachably mounted at the forward end of said table, and each bar is provided at its free end with an extension to bear against the underlying bar to thus prevent sagging of said bars, which may be
- 10 caused when feeding the web over said bars, the lowermost bar bearing against a fixed bracket.

With this arrangement, in order to prepare the web for a work-sheet-shifting operation, the feed-rolls are first cast off and then the carbon-carrier is pushed rearwardly, to withdraw the web around the platen to arrest the carbon-sheets with their leading edges clear of the platen. The feed-rollers are then again thrown on to advance the work-sheets while the carbon-sheets are held, until the leading edges of the work-sheets reach a gage arranged at the delivery side of the platen. The work-sheets and the carbon-sheets may then be fed around the platen together, until the leading edges of the work-sheets reach a second gage, at which time the carbon-sheets have reached the printing point, and the bottoms of the typed forms have reached a knife, where they may be severed.

A feature of the invention relates to means to enable the work-sheet-displacement gage to be set for comparatively short forms relatively to a front paper-table over which the work-sheets pass from the platen. To this end, there is provided, in said table, a cutout into which said gage may extend when adjusted for a small form. Said gage is so positioned with respect to the gage-bar, upon which it is adjustably mounted, when set for long forms, as to be behind the plane of the gage-bar so as not to interfere with the leading edges of the work-sheets while they are being advanced from said gage to the second gage. When the work-sheet-displacement gage is adjusted for a small or short form, it is disposed below the face of the front table so as not to interfere with the leading edges of the work-sheets.

Other features and advantages will hereinafter appear.

In the accompanying drawings.

Figure 1 is a sectional side view of a portion of an Underwood typewriting machine, showing the invention applied thereto, the parts being shown in the positions they occupy near the end of typing of a set of forms.

60 Figure 2 is a view similar to Figure 1, and shows the feed-rollers released and the carbon-carrier pushed to its rearmost position to condition the web for a work-sheet-shifting operation.

65 Figure 3 is a view similar to Figure 2,

with some of the parts omitted, and showing the work-sheets shifted relatively to the carbon-sheets by advancing them around the platen to the first gage.

Figure 4 is a view similar to Figure 3, and shows the work-sheets advanced with the carbon-sheets around the platen, the work-sheets being advanced to the second gage to thus bring the carbon-sheets to the printing point and the bottoms of the typed forms or portions of the work-sheets to the knife.

Figure 5 is a fragmentary top plan view of the typewriter-carriage and a portion of the rearwardly-extending table.

Figure 6 is a sectional view, taken on the line 6-6 of Figure 1, and looking in the direction of the arrows.

Figure 7 is a perspective view showing the forward portion of the table and the guide-bars, the parts being disassembled for clearness.

The invention is shown as applied to an Underwood standard typewriting machine, in which type-bars 10, when operated by keys, not shown, swing upwardly and rearwardly to print against the front of a cylindrical platen 11, mounted on a carriage 12 comprising end bars 13 connected to each other by a rear bar 14 and a front bar, not shown, said carriage being mounted for letter-feed movements on a rear rail 15 and a front rail, not shown, said rails being supported on the main frame 16 of the machine. The platen is secured to a shaft 17 journaled in end plates 18 of a platen-frame 20, said end plates being secured to each other by a bar 21 and a rear paper-table 22, over which a composite work-web 23 is led from the back of the machine to the rear and beneath the platen where there are provided feed-rollers 24 and 25 to assist in feeding the work-web around the platen. The platen may be rotated by a finger-wheel 26 or line-space wheel 27, the latter being operable by suitable line-space mechanism, not shown.

105 The platen-frame is supported on the carriage-frame for case-shifting movements in the usual way to present the platen to lower-case types 30 or upper-case types 31 on the type-bars. The feed-rollers may be released by mechanism operable by the regular feed-roller release handle 28, so as to provide an unobstructed path around the platen when adjusting the work-web around the platen.

110 The device is in the nature of an attachment which may readily be applied to any standard typewriting machine, and comprises a horizontal table 32 extending rearwardly from the platen, said table supporting the composite web 23, said web passing over said table to the platen and being composed of work-sheets 33 with interleaved carbon-sheets 34 therebetween. The table 32 comprises end bars 37 connected to each other by a front cross-bar 40 and a rear cross-bar 115 120 125 130

41, and is supported to travel with the carriage 12. The table 32 is connected with said carriage, for this purpose, by rearwardly-extending brackets 42 secured to the 5 under side of the carriage-bar 14 and to the under side of the cross-bar 40 of said table. The two end bars 37 have rails 45 secured thereto to guide a carbon-carrier 46 in its 10 movement towards and away from the platen. The carbon-carrier comprises a base-plate 47, to the under side of which are attached four rollers 48, two at each side of the machine, to run on the rails 45. The carbon-carrier further comprises stepped uprights 15 50, one at each side of the base-plate 47, upon which the carbon-carrying blades or holders 51 are detachably mounted, said carbon-carrying blades having connected thereto the rear ends of the carbon-sheets 34. The work- 20 web 23 may be composed of separate plies, or the plies may be connected alternately at their opposite sides to form a fan-fold, as indicated in Figure 6. Said work-web may be conducted from any suitable source of 25 supply upwardly at the rear of the machine to a turning bar 52, supported by standards 53 and provided with suitable end gages 54 for the web. From the turning bar the web extends forwardly through the carbon-carrier, where the carbon-sheets become interleaved between the plies of the web. The web is then bent downwardly at 56 in front of the table 32 towards the platen.

In the bend 56 of the work-web there is arranged a set of guide-bars 57 or separators over which the work-sheets are conducted, there being one guide-bar for each ply or work-sheet 33 to thus hold the work-sheets separated from each other and consequently 30 avoid binding of the carbon-sheets 34 between the work-sheets at said bend 56. This separation of the work-sheets enables them to be readily shifted relatively to the carbon-sheets as hereinafter described.

45 After a set of forms has been typed, the work-sheets having reached the position indicated in Figure 1, it is necessary to cause a relative displacement or shifting between the carbon-sheets and the work-sheets, or, in 50 other words, strip the carbon-sheets from the typed portions of the work-sheets. To this end, the feed-rollers 24 and 25 may first be released by means of the feed-roller-release lever 28, thus enabling the web to be freely withdrawn around the platen by pushing rearwardly the carbon-carrier 46 by means of its handle 58, until the carbon-carrier is arrested by a fixed stop 60 on one of the end bars 37, thus bringing the 55 leading ends of the carbon-sheets free of the platen, as indicated in Figure 2. The leading edges of the work-sheets, however, are left between the platen and the rear feed-rollers 25. The feed-rollers 24 and 25 are 60 then thrown on and the platen is rotated to

feed the work-sheets 33 forwardly while the carbon-sheets 34 are held by the carbon-carrier. The extent of this forward movement of the work-sheets is determined by a gage or indicator 61 on a gage-element 59 adjustably secured to a staff or gage-bar 62 by a thumb-screw 59a. The gage-bar 62 is secured to a cross-bar 63 mounted on the end plates 18 of the platen-frame. The work-sheets are advanced until their leading edges come opposite said gage 61, as indicated in Figure 3.

After shifting the work-sheets, they are advanced with the carbons, by a further rotation of the platen, to bring a fresh set of forms with the carbon-sheets to the printing point. It will be understood that there is a tendency for the carbon-sheets to travel forwardly with the work-sheets due to frictional contact of the work-sheets with the carbon-carrier and the pressing together of the carbon-sheets 34 between the work-sheets behind the platen. This tendency is overcome, however, during a work-sheet-shifting operation, by holding the carbon-carrier, as previously explained. To determine the extent of feed of the work-sheets when a fresh set of forms is being brought to the printing point with the carbon-sheets, there is provided a second gage 64 on the gage element 59 to which the leading edges of the work-sheets 33 are brought, as shown in Figure 4. The typed portion of the work-sheets, or, in other words, the typed set of forms, may be severed after the work-sheets have been brought to the gage 64 by drawing them forwardly against a knife 65 suitably mounted on a table 66 supported on the cross-bars 63.

The guide-bars 57 may readily be assembled on the machine, and, for this purpose, they are detachably mounted on the forward end of the rearwardly-extending table 32, said table being provided with two blocks 70, each having an upwardly-extending standard or screw 71, the screws 71 passing through holes 72 in rearward extensions 73 of the guide-bars. The guide-bars are superposed, and are provided with spacers 74 to properly space them from the blocks 70 on the table and from each other. They are fastened on the table by thumb-nuts 75 threaded onto said standards 71. The free ends of the guide-bars are provided with down-turned lips 76, each engaging its underlying guide-bar to prevent sagging of the bars, the lip of the lowermost guide-bar bearing on a bracket 77 secured to one of the bar-supporting blocks 70. Dowel-pins 80 are provided to enter holes 81 in the spacers 74 of the guide-bars to firmly hold said guide-bars against any pivotal displacement about the standards 71, the two lowermost guide-bars being held by the dowel-pins extending upwardly from the bar-supporting blocks 70. The guide-bars above the two lowermost 130

are held by the dowel-pins extending upwardly from the underlying guide-bars. It will be understood that the standards for holding the guide-bars may be of any length, so that any number of guide-bars may be assembled according to the number of plies in the work-web.

The table 66 is provided with a cutout 82 which the gage 61 may enter when set for comparatively short forms, the face of the gage being flush with or slightly below the face of the table 66 so as not to catch on the upper edges of the work-sheets as they are fed past said gage.

15 To guide the forward end of the web 23 as it passes through the guide-bars or spacers 57 and to the platen, and thus avoid accidental sidewise displacement of said web, there are provided side-edge guides 83 adjustably secured to a bar 84 supported on the table 32.

Variations may be resorted to within the scope of the invention, and portions of the improvements may be used without others.

25 Having thus described my invention, I claim:

1. In a continuous billing typewriting machine, the combination of a carriage, a platen on said carriage around which may be fed a composite web comprising plies of work-sheets interleaved with carbon-sheets, the web being bent in its path to the platen, means to free the carbon-sheets from said platen, and narrow concavo-convex 35 spacer guides mounted, one above another, a short distance apart with their convex sides up, a single ply of the web and a carbon-sheet being threaded between each two adjacent guides, all of said guides being disposed in the bend of the web and away from the platen and being effective to facilitate relative shifting between the plies and the carbon-sheets after said carbon-sheets have been freed from the platen.

45 2. In a continuous billing typewriting machine, the combination of a carriage, a platen on said carriage around which may be fed a composite web comprising plies of work-sheets interleaved with carbon-sheets, the web being bent in its path to the platen, means to free the carbon-sheets from said platen, oppositely-disposed narrow concavo-convex spacer guides detachably mounted, one above another, a short distance apart with their convex sides up, a single ply of the web and a carbon-sheet being threaded between each opposite pair of guides, all of said guides being disposed in the bend of the web and away from the platen, feed-rolls to advance the plies while the carbon-sheets are held, and a gage to determine the extent of advance of said plies.

65 3. In a continuous billing typewriting machine, the combination of a carriage, a

platen on said carriage around which a composite web comprising plies of work-sheets, may be fed with interleaved carbon-sheets, the web being bent in its path to the platen, means to free the carbon-sheets from said platen, guides, one for each work-sheet, said guides being disposed in the bend of the web, feed-rolls to advance the work-sheets while the carbon-sheets are held, a gage to determine the extent of advance of the work-sheets, a second gage to determine the extent of feed of the work-sheets with the carbon-sheets after the work-sheets have been shifted, and a knife to sever the typed portions of the work-sheets.

4. In a continuous billing typewriting machine, the combination with a carriage, a platen on said carriage around which may be fed a composite web including plies of work-sheets interleaved with carbon-sheets, and means to free the carbon-sheets from said platen, of a nested stack of narrow concavo-convex spacer guides, one for each work-sheet being mounted in the bend of the web with its convex side up, said guides being supported on said carriage and extending alternately from opposite sides of the carriage, the free end of each guide having a downwardly-extending lip for engaging the next lower guide near its fixed end, and a piece fast on said carriage for supporting the lip of the lowermost guide.

5. A separator for insertion between superposed plies of a work-web in a typewriting machine, including a narrow plate having a concavo-convex cross-section positioned convex side up, a downwardly-turned lip at its inner end and a short transverse arm at its outer end, and a mounting pad fastened to the under side of said arm, said pad and arm having a mounting hole through them.

6. A separator for insertion between superposed plies of work-web in a typewriting machine, including a narrow plate having a concavo-convex cross-section positioned convex side up, a downwardly-turned lip at its inner end, and a short transverse arm at its outer end disposed substantially tangent to the middle portion of the convex side of said plate, a mounting pad fastened to the under side of said arm, said pad having a centrally-located mounting hole extending through it and the superposed arm, and a smaller hole on each side of the mounting hole that extends partly through said pad, and two short dowel-pins extending upwardly from the surface of said arm and positioned opposite said smaller holes in said mounting pad.

7. In a continuous billing typewriting machine, the combination of a carriage, a platen on said carriage around which a composite web comprising plies of work-sheets may be fed with interleaved carbon-

sheets, the web being bent in its path to the platen, means to free the carbon-sheets from said platen, guides, one for each work-sheet, said guides being arranged in the bend of the web and being effective to facilitate relative shifting between the work-sheets and the carbon-sheets after the carbon-sheets have been freed from the platen, standards located at each end of said carriage, and means to secure said guides on said standards.

8. In a continuous billing typewriting machine, the combination of a carriage, a platen on said carriage around which a composite web comprising plies of work-sheets may be fed with interleaved carbon-sheets, the web being bent in its path to the platen, means to free the carbon-sheets from said platen, guides, one for each work-sheet, said guides being arranged in the bend of the web and being effective to facilitate relative shifting between the work-sheets and the carbon-sheets after the carbon-sheets have been freed from the platen, standards located at each end of the carriage, means to properly position said guides relatively to said carriage, and means to secure said guides on said standards.

9. In a continuous billing typewriting machine, the combination of a carriage, a platen on said carriage around which a composite web comprising plies of work-sheets may be fed with interleaved carbon-sheets, the web being bent in its path to the platen, means to free the carbon-sheets from said platen, guides, one for each work-sheet, said guides being arranged in the bend of the web and being effective to facilitate relative shifting between the work-sheets and the carbon-sheets after the carbon-sheets have been freed from the platen, a rearward extension on said carriage, standards on said extension to fasten said guides, and means comprising dowels to hold said guides in place.

10. In a continuous billing typewriting machine, the combination of a carriage, a platen on said carriage around which a composite web comprising plies of work-sheets may be fed with interleaved carbon-sheets, the web being bent in its path to the platen, means to free the carbon-sheets from said platen, and guides, one for each work-sheet, said guides being arranged in the bend of the web, said guides being supported on said carriage and extending alternately from opposite sides of the carriage, the free end of each guide having an extension for its support by engaging the adjacent guide, and a fixed bracket with which the extension of the lowermost guide engages.

11. In a continuous billing typewriting machine, the combination with a carriage,

a platen around which a composite web including plies of work-sheets may be fed while interleaved with carbon-sheets, said web being bent in its path to the platen, and means to free the carbon-sheets from said plies, of a stack of narrow concavo-convex nested spacer guides, one of said guides being disposed below each work-sheet and mounted in the bend of the web with its convex side up, a paper-table at the delivery side of said platen, and a gage adjustably mounted on said table for determining when to free said carbon-sheets from the leading ends of said plies prior to severing a set of superposed typed forms from said web, the lower end of said gage being movable behind said paper-table and the latter being provided with a cut-out to permit the lower end of said gage to be visible for gaging short forms.

12. In a continuous billing typewriting machine, the combination of a carriage, a platen on said carriage around which a composite web comprising continuous work-sheets may be fed with interleaved carbon-sheets, a table at the introductory side of said platen, said table comprising a straight section extending rearwardly from the platen and guide-plates at its forward end, said guide-plates being curved downwardly towards the platen, a carbon-carrier to which the carbon-sheets are attached, said carbon-carrier being supported on said table and movable towards and away from the platen on the straight extension of said table, means to move said carbon-carrier rearwardly to free the carbon-sheets from said platen, feed-rollers co-operating with said platen to shift the work-sheets while the carbon-sheets are held, a gage to determine the extent of shift of the work-sheets, a second gage to which the work-sheets may be advanced while they are fed with the carbon-sheets to bring the latter to the printing point, and a knife to sever the typed portions of the work-sheets.

13. In a typewriting machine, the combination of a revoluble platen around which work-sheets may be fed with interleaved carbon-sheets, superposed separators for said work-sheets, said separators extending alternately from opposite sides of the machine, means to fasten said separators, and means comprising dowels to prevent accidental displacement of said separators.

14. In a typewriting machine, the combination with a platen, of a paper-table at the delivery side of said platen, an upwardly-extending gage-rod in the back of said table, and a downwardly-extending gage adjustably mounted on said rod, the lower end of said gage being movable behind the plane of said table, the latter having a cut-out opposite said gage for permitting the

lower end thereof to be visible while in position below the top edge of said paper-table.

15. In a continuous billing typewriting machine, the combination of a carriage, a platen on said carriage around which a composite web comprising plies of work-

sheets may be fed with interleaved carbon-sheets, a table at the delivery side of the platen, said table having a cut-out, a gage-bar on said table, and a gage adjustable on said bar, said cut-out being provided for the reception of said gage. 10

JOHN WALDHEIM.
